United States Patent Office

Des. 183,009

Patented June 10, 1958

183,009

CHAIR

Charles Mackintosh, Los Angeles, Calif.

Application June 12, 1956, Serial No. 41,878

Term of patent 14 years

(Cl. D15—1)

I claim:

The ornamental design for a chair, as shown.
